UNITED STATES PATENT OFFICE.

CHARLES T. RASCHICK, OF ST. PAUL, MINNESOTA.

MANIFOLD SALES BOOK.

Application filed April 3, 1922. Serial No. 549,314.

My invention relates to improvements in manifold sales books and is particularly adapted to that class of book where an original order is written upon a check and duplicates are made of the items of the order either individually or severally so that the duplicates can be used in different departments and checked back to the original order. This manifold book is used very extensively 10 in restaurants where it is desired to keep a check on the original orders.

A feature of the invention resides in the attaching or clamping of several pads to a cover in a suitable manner so that they can 15 be selectively positioned for writing upon the faces of the respective pads without requiring a complicated holder in which the parts are pivoted together.

It is also a feature of the invention to provide holding means for the pads which will support one pad superposed to the other, the holding means for each pad providing a rigid back or support so that even the last sheets of the pad may be readily written 25 upon either separately or in conjunction with the other pad.

The invention also includes means for slidably securing the superimposed pad to the cover. The slideable supporting means are 30 secured to the cover of the book in a manner to prevent disengagement of the same, but to freely receive a new pad when the old pad is used up.

A still further object is to provide means 35 for separating turned over leaves from fresh leaves of the original sales check pad when the former have been turned back to add further written matter to a particular leaf.

A still further object is to provide a fixed 40 arm attached to the cover of the book for holding used leaves of the original sales check pad aloof from the remainder of the pad.

The novel feature of the invention will be 45 more clearly and specifically pointed out in the specification and following claims.

In the drawings forming part of this specification:

Fig. 1 is a plan view of my manifold book 50 in open position.

Fig. 2 is a side elevation of the device shown in Figure 1.

Fig. 3 is a plan view of the invention with the parts in a different position.

Fig. 4 is a central longitudinal enlarged

cross section with the book in closed position.

Fig. 5 is an enlarged central longitudinal cross section illustrating the book in open position as it would appear in use. 60

Fig. 6 is a side elevation of a portion of the book in open position, parts of which are broken away.

Fig. 7 is a bottom view of a portion of the pad holding means. 65

Fig. 8 is a cross section on line 8—8 of Figure 7 illustrating the complete width of the manifold book.

In the drawings the manifold book A is composed of a cover having a bottom portion 10, to which is hingedly secured the top flap 11. The flap 11 is adapted to fold over to enclose the pads held in the cover as illustrated in Fig. 4. The parts 10 and 11 are formed of a substantially stiff material while a portion 12 forming the hinge or connection and which is interposed between the parts 10 and 11 is of a flexible nature. 70 75

The book A is arranged to carry or support two pads of checks B and C, the pad B composing the checks for the original order and the pad C the checks for the duplicates of the items indicated on the original order. The pad B is held at its stapled end by means 80 of a spring clamp 13 which is positioned adjacent the hinge of the cover of the book while the body of the check is supported within a channel shaped member 14 having upwardly projecting side walls 15 and which 85 is formed of metal or other suitable material. The member 14 is rigidly attached to the back 10 of the cover by means of the rivets 16 so as to firmly secure the member against disengagement therefrom. 90 95

The pad of checks C is held slidably superimposed to the pad B by means of a supporting member 17, which is formed with a smooth flat upper surface 18 upon which the pad C rests. Projecting downward from the face 18 of the member 17 are side members 19 on the free end of which is formed an inwardly projecting longitudinally extending flange 20. The side members 19 are adapted to fit within the side walls 15 of the member 14 while inturned flanges 20 formed on side walls 15 engage beneath longitudinally extending side edges 21 of the member 14 which are end spaced above the portion 10 of the cover by means of de- 100 105 110

pressed portions 22 and 23 formed in the lower surface of the member 14. The portions 22 extend along the side edges of the member 14 while sockets 23 are adapted to receive the rivets 16. The forward end of the flanges 20 of the member 17 are formed with inwardly projecting shoulders 24 which engage against a depressed portion 25 formed in each of the rearmost portions 22 after the flanges 20 have been inserted beneath the edges 21 far enough to admit the shoulders 24. This is clearly illustrated in Figures 7 and 8.

The member 17 is held freely slidable within the sides 15 of the member 14 while the pad B is slightly narrower than the space between the sides 15 so that when the pad B is inserted in the clamp 13 its body portion will extend between the sides 15 leaving a space 26 on each side of the same with the free ends of the pad extending a short distance below the head end of the member 17. This holds the free ends of the pad B beneath the member 17 and allows the member 17 to engage a sufficient portion of the member 14 so as to form a rigid structure for the member 17 when it is pulled in outwardly position as illustrated in Figure 6. The spaces 26 on either side of the pad B permit the side members 19 to slide freely without interfering with the sides of the pad B.

The pad C is held firmly to the surface of the slidable member 17 by the spring clamp 27. When the member 17 is slid forward into the position illustrated in Figures 4 and 5 the body of the pad B is practically enclosed within a box-like supporting means which is formed between members 14 and 17, and the pad C is held superimposed to the pad B.

A spaced loop formed of wire or other suitable material 28 is pivotally attached to the lower portion of the head end of the member 17 and the free end 29 of this loop slides along over the face of the pad B. After the sheets 30 of the pad B have been lifted from beneath the member 17 and written upon and it is desired to insert them again beneath the pad C they are for convenience inserted over the free end of the loop 28 as illustrated in figure 6. A notch 31 formed in one of the sides 15 allows the loop 28 to be readily engaged and raised which has a tendency to lift the ends of the reinserted sheets 30 from beneath the head end of the pad C.

A shoulder 32 formed on the lower surface of the member 14 engages the inner edge 33 of the member 17 to limit its inward movement over the pad B. An engaging tongue 34 is formed on the rear edge of the member 17 so that the same can be withdrawn into the position illustrated in Figure 6 when desired.

In using my manifold sales book a sheet 30 is raised from the pad B while the pads are in the position illustrated in Figure 6, and after the pad C has been slid forward into the position illustrated in Figure 5, superposed to the pad B, the sheet 30 is laid over the top sheet 35 of the pad C with a sheet of carbon 36 interposed between the same and the order is then written upon the sheet 30, which is duplicated by the carbon to one of the sheets 35. When my manifold book is used in connection with restaurant orders the sheet 30 is not removed

until the customer has completed his order but is turned back out of the way beneath the arm 37 secured to the cover portion 11.

The next sheet 30 of the pad B can then be used in the same manner duplicating on the pad B by sliding the pad C back and forth into the desired position. Should one of the

customers who has already given his order desire to give a further order the particular sheet 30 upon which his order is written is selected from among the sheets which are turned back beneath the arm 37 and the un-

desired sheets beneath the particular check desired are inserted as illustrated in Figure 6 beneath the pad C and above loop 28 while the desired check or sheet 30 is laid over the pad C as illustrated in Figure 5 and another

duplicate is made upon the upper check of the pad C. In this manner several duplicates may be made from the same original check and also not requiring more than one original check for each customer. This sys-

tem is a very desirable record for restaurant keepers and other merchants who have to keep a check on their sales and the simple ef-

fective manner in which the pads B and C are held so that they can be replaced and so that the pad C can be superposed to the pad B

allowing the waiter or clerk to readily take orders and report on the same. A slidable support for the pad C is preferable to any pivoted holding means, the slidable support being hinged to the cover of the book and forming a much more substantial support for the pad. It is very desirable to have a

substantial neat inexpensive manifold book so that the waiter can easily carry the same in his pocket and one which will not easily get out of order or cause any inconvenience in its use, holding all of the checks in a neat and tidy manner.

In accordance with the patent statutes I have described the principles of operation of my invention, together with the apparatus which I now consider to represent the best embodiment thereof, but I desire to

have it understood that the construction shown is only illustrative and that the invention can be carried out by other means and applied to uses other than those above set forth within the scope of the following claims.

I claim:

1. A manifold sales book comprising a cover, a pad secured to said cover and inclosed by side walls, a second pad slidably mounted over said first pad and notches in said side walls to allow ready access to the sheets of said first pad.
2. A sales book including a pad of original checks, and a pad of duplicating checks, means for holding said original checks, and means for slidably holding said duplicating checks superimposed over said original checks.
3. A sales book comprising a cover, a pad of checks bound at one end, secured to said cover, a second pad of checks mounted slidably above said cover and falling short of the bound end thereof so that the uppermost leaf of said first pad may be separated from the body thereof and placed over said second pad.
4. A manifold sales book including a cover, a spring clamp secured to said cover for attaching a pad of checks to said back, a track secured to said back, a support for a pad of checks including a clamp slidably secured to said track whereby one pad of checks is superposed in relation to the other so as to be moved away from the writing face of the other.
5. A manifold sales book comprising a cover, a pad of checks mounted on said cover, a second pad positioned above the first pad, and means for slidably supporting said second pad in spaced relation to said first pad so that said second pad may be bodily moved over or away from said first pad in a plane parallel thereto.
6. A manifold sales book comprising a cover, a pad secured to said cover, a second pad positioned over said first pad in a plane parallel thereto, and means for slidably supporting said second pad within said plane independently of said first pad.
7. A sales book comprising a pad of checks adapted to be separated between any of the checks thereof and a slidable support for a second pad of checks arranged to be slid between the separated portions of said first named pad of checks.
8. A sales book comprising a cover, a pad of checks mounted thereon, said pad of checks being adapted to be separated between any of the checks thereof, a second pad of checks arranged to be positioned between the separated portions of said first pad of checks and means for slidably supporting said second pad of checks upon said back.
9. A manifold sales book including a cover, a pad of checks mounted thereon, a pair of channels depressed in said cover,

lugs formed on said cover issuing outwardly into said channels, a back, a second pad of checks mounted on said back, and means secured to said back slidable within said channels and beneath said lugs whereby the back may be reciprocated over said cover.

10. A manifold sales book including a cover, a pad of checks mounted thereon, a pair of channels depressed in said cover, lugs formed on said cover issuing outwardly into said channels, a back, a second pad of checks mounted on said back, means secured to said back slidable within said channels and beneath said lugs whereby the back may be reciprocated over said cover, and a stop formed on one of said lugs for terminating the movement of said back.

11. A manifold sales book including a cover, a check pad mounted on said cover, a back slidably mounted on said cover, positioned over said check pad, a second check pad mounted on said back, a separating member secured to said back resting upon the exposed leaves of said first pad, and protruding means formed on said separator adapted to be engaged by the fingers to lift and separate any superimposed leaves placed upon the same from the remainder of the pad.

12. A manifold sales book comprising a cover, a pad of checks mounted thereon, a back slidably mounted on said cover and positioned over said pad of checks, a U-shaped wire member pivoted to said back and resting upon the upper surface of said first check pad to separate checks superimposed upon the same from the remainder of said check pad.

13. A manifold sales book including a cover, a pair of upturned flanges formed on said cover, a back slidable between said flanges, a second check pad mounted on said back, said second check pad and back being movable over or away from said first check pad, a U-shaped wire member pivoted to said back and resting upon the upper surface of said first named check pad, and a notch formed in one of said flanges in proximity to said wire member when the second pad is remotely positioned from the first pad whereby said wire member may be engaged by the fingers to separate leaves which may have been superimposed above the same from the remainder of the first named pad.

14. A manifold sales book comprising a cover, a pad secured to said cover, a second pad slidably mounted over said first pad and leaf retaining means upon said cover for the purposes specified.

In testimony whereof I affix my signature.
CHARLES T. RASCHICK.
